UNITED STATES PATENT OFFICE

GEORGE W. LANCASTER, OF RICHMOND, VIRGINIA

WINDOW-FRAME CONSTRUCTION

Application filed August 13, 1929. Serial No. 385,520.

This invention relates to sheet metal window frames provided with sliding sashes.

The object of the invention is to provide a frame of simple construction by which the 5 sashes can be readily removed from their frame without altering or in any way disturbing the jambs of the window frame.

Other objects of the invention will become apparent as the detailed description thereof 10 proceeds.

In the drawings:

Figure 1 is an elevation of one stile of a window frame, with the head and sill of the frame shown in section, and a false head removed, both sashes being shown in raised 15 position;

Figure 2 is a fragmentary elevation of the said stile, with the sill shown in cross section, and both sashes lowered;

20 Figure 3 is a fragmentary elevation of the upper part of said stile, with both sashes raised to contact with the false head (shown in section) of the frame;

Figure 4 is a horizontal transverse section 25 of the window frame taken between the sill and head thereof, and showing one of the parting beads removed from one of the stiles;

Figure 5 is a fragmentary perspective view 30 of parts of the false head of the window frame;

Figure 6 is a perspective view of a parting bead forming part of this window frame;

Figure 7 is an elevation of a window stile 35 in a modified form of the invention and showing the sashes raised in the frame;

Figure 8 is a similar elevation showing the sashes lowered;

Figure 9 is a horizontal transverse section, 40 to an enlarged scale, of a window jamb, taken on the line 9—9 of Figure 8;

Figure 10 is a fragmentary vertical section through one of the parting beads used in the modification;

45 Figure 11 is a perspective view of an intermediate section of the last named parting bead;

Figure 12 is a horizontal section taken between the sill and head;

50 Figure 13 is a horizontal section showing

the removable stile member and sash in dotted lines;

Figure 14 is a section taken on the line 14—14 of Figure 13;

Figure 15 is a perspective of the removable 55 stile member; and

Figure 16 is a perspective of the removable parting bead.

In the form of the invention illustrated by Figures 1 to 6, the reference numerals 1 and 2 designate the opposing stiles of the window frame; connected at one end by the head 3, and at the other end, by the sill 4.

Each stile has a wide slot 5 extending throughout its length from sill to head; and 65 a V-shaped channel member 6 is bolted, or otherwise secured, to the back of the stile to stiffen the stile and to form a long recess in which the tongues 7 and 8 of the sashes 9 and 10, respectively, are adapted to slide.

At opposite sides of the slot 5, the stile has inturned flanges 11 and 12, adapted to form smooth guiding surfaces for weather strips 13 and 14 secured to the tongues 7 and 8, respectively.

The tongues 7 and 8 are separated from each other by a parting bead extending from the top of the sill 4 to the bottom of the head 3. The parting bead comprises two aligned sections 15 and 16, the lower section being 80 slightly longer than either of the sashes 9 and 10. The purpose of this construction is illustrated in Figure 4 of the drawing. It

will be obvious from inspection of this figure that when the lower section 16 is removed from the stile 1, either of the sashes 9 and 10 may be moved into the recess, formed by channel member 6, to permit the tongues 7' and 8' at the opposite stiles of the sashes 9 and 10 to be slipped out from the slots 90 formed by the inturned flanges 11' and 12' of the stile 2 and the parting bead seated in the channel members 6'.

The head 3 of the window frame is not the 95 finish head of the frame; it is merely a box which permits both sashes 9 and 10 to slide clear above the joint 17 between the sections 15 and 16 in order to permit the removal of the lower section 16. The finish head 18 (shown clearly in Figures 3 and 5) has flanges 100

19 and 20 formed on its opposite edges and adapted to seat over flanges 21 and 22, formed on the head 3, and be secured thereto by screws 23 and 24, or any other suitable securing means. The finish head 18 is really the soffit of the frame, and is provided with a groove or recess 25, adapted to receive, with weather tight fit, the head of the upper sash 10.

10 It will be understood, of course, that at least one of the channel members 6 or 6' must be of sufficient depth to permit either the sashes 9 and 10 to slide thereinto, when the section 16 is removed, in order to free the tongues 7' and 8' from the stile 2. The main thing in this construction is to form the several parts so that the sashes can be removed from the frame without disturbing either of the stiles 1 and 2. When the sashes 20 are removed, either or both of the stiles can be readily disconnected and removed from the jambs 26 and 27, respectively. The head 3, sill 4 and jambs 26 and 27 are suitably welded or otherwise permanently secured to each other; while the soffit 18 and stiles 1 and 2 are detachably connected to the head 3 and the said jambs, respectively.

15 The upper ends of the channel members 6 and 6' are provided with the usual pulley 30 sheaves 28 and 29 for the chains or cables 30 and 31 connecting the sashes 9 and 10 to their counterbalance weights 32 and 33, respectively.

20 In prior constructions of sheet metal windows, the repair of broken counterbalance chains or the parts of the frame and sash have necessitated the bodily removal of the whole stiles and sashes. In the present form, the sashes can be removed first from the frames, and the stiles can then be removed separately to give access to the counterbalance weights. As a matter of fact, the lower parts of the channel members 6 and 6' can be provided with pockets 34 (see Figure 2) back of the parting beads, to give 25 access to the weights and provide for the hanging of the sashes in the same manner as the common wooden sashes are ordinarily hung in the usual wooden frames.

25 In the modification shown in Figures 7 to 11, inclusive, the soffit 18 need not be removed in order to effect removal of the sashes from the frame. In this form, one of the parting beads is made in three sections 35, 36 and 37. The upper section 35 ends at a distance above the sill 4 greater than the length of either of the sashes; and has the lower end of its front face provided with a lip 38 adapted to seat snugly in the side 30 channels 39 and 40 of the section 36.

35 The lower end of the section 36 is likewise provided with a lip 41 adapted to seat in the upper end of the section 37, screw bolts 42 and 43 being used to secure the three sections to 40 each other.

30 Of course, the section 36 may be of any desired length, providing the combined length of sections 36 and 37 is greater than the length of the lower sash. It is more convenient to move the sashes to the lower end of the frame to effect their removal; but it is obvious that the construction can be changed so that the sashes can be removed from any part of the frame. All that is necessary is to provide for the removal of some or all of a 35 parting bead longer than the length of either or both sashes.

35 In the form of the invention illustrated by Figures 12 to 16, inclusive, an inner and outer stile 2 is shown on both sides of a window. Both the inner and outer stile 2 is divided into two sections, only the lower inner sections 2' being removable. The stile 2 is made integral and bent so as to form a channel for the sash 9. The outer stile sections 2' are secured to the frame by a screw 44. The inner side, which is in the form of an inturned flange 11, is held in place by a screw 45, which also holds the parting bead 16; the inturned flange seating beneath the parting bead 16, with an aperture 46 therein alining exactly with the screw 45 in the parting bead 16.

40 On the opposite side of the window, exactly the same construction is used so that upon the removal of the corresponding elements on the opposite sides, the lower sash 9 may be removed, and upon the upper sash 10 being lowered to a position corresponding to the lower sash 9 and upon the removal of the parting bead, it likewise can be removed.

45 The removal operation consists in, first, the removal of screw 44, which will release one end of the stile member 2, and then unscrewing the screw 45 until it is raised sufficiently to permit the withdrawal of the in-turned flange 11. It is to be noted that the screw 45 will still retain the parting bead in place, which is not entirely withdrawn from the channel member 6. Upon this operation being completed the lower sash 9 may be lifted from the window frame.

50 If it is desired to also remove the upper sash 10, the same may be lowered to the position usually occupied by the lower sash 9, and upon the screw 45 being unscrewed, the parting bead 16 may be lifted from the channel 55 6, which permits the ready removal of the upper sash 10.

55 It will be understood, of course, that only the lower portion of the parting bead is to be removed, and further that exactly the same operation may be performed on the opposite side of the window with the same result, since the construction is identical on both sides.

60 What I claim is:

65 1. A window frame having the opposite stiles thereof provided with slots, a channel member secured to the back of each stile across the slot therein, a pair of sashes having tongues on the opposite stiles thereof 70

slidable in said slots, and parting beads detachably secured to the bottom of each channel member for slidably engaging the adjacent tongues of said sashes and to lock the sashes slidably in said frame.

5 2. A window frame having the opposite stiles thereof provided with slots, a channel member secured to the back of each stile across the slot therein, a pair of sashes having 10 tongues on the opposite stiles thereof slidably in said slots, and parting beads detachably secured to the bottom of each channel member for slidably engaging the adjacent tongues of said sashes and to lock the sashes 15 slidably in said frame, one of said channel members being at least as deep as the combined width of the tongues on the stiles of each sash.

20 3. A window frame having the opposite stiles thereof provided with slots, a channel member secured to the back of each stile across the slot therein, a pair of sashes having 25 tongues on the opposite stiles thereof slidably in said slots, and parting beads detachably secured to the bottom of each channel member for slidably engaging the adjacent tongues of said sashes and to lock the sashes slidably in said frame, one of said channel members being at least as deep as the combined width of the tongues on the stiles of each sash, the parting bead in the last 30 named member being divided into removable sections, one of which is longer than the length of either of said sashes.

35 4. A window frame comprising a pair of channel shaped jambs, a sill fixed to one end of said jambs, an inverted channel shaped head fixed to the other ends of said jambs, a pair of stiles detachably secured to said jambs and each having a slot extending lengthwise thereof, parting beads, means for securing said beads to said stiles to form a pair of parallel slots with the edges of said slot in each stile, a pair of sashes having tongues slidable in said parallel slots and slidable into and out of said head and a soffit detachably connected to said head and provided with a weathering recess to receive the upper rail of the outer sash, one of said parting beads having a detachable section longer than the length of either of said sashes.

50 5. A window frame comprising a pair of channel shaped jambs, a head and a sill fixed to the opposite end of said jambs, a pair of stiles having grooves formed therein and detachably connected to said jambs, a parting bead detachably secured to the bottom of the groove in each stile and forming with the edges of said groove a pair of parallel slots, and a pair of sashes having their stiles provided with tongues slidable in said slots, one of said beads being formed in sections removable to permit either sash to move laterally into the groove of stile supporting the sectioned bead, said groove being deeper than

the combined widths of the tongues on either sash.

6. A window frame comprising a pair of channel shaped jambs, a pair of stiles detachably secured to said jambs and having slots 70 extending throughout their lengths, channel members secured to the backs of said stiles across the slots therein, a parting bead detachably secured in each channel member and having its side edges spaced from the edges of said slot to form a pair of parallel slots, each of said beads being formed in sections 75 one of which is less than one-half the length of the stile, a pair of sashes having tongues slidable in said parallel slots, and means for counterbalancing said sashes, said channel members being provided with detachable pockets at the back of one of said removable sections.

7. A window frame comprising an inner and outer stile, said inner stile divided into an upper and lower section, one of said sections removable from said frame, a parting bead intermediate said stiles to form channels, window sashes seated in said channels, said parting bead divided into an upper and lower section, the upper or lower section of said parting bead opposite the removable portion of said inner stile removable, the removable portion of said stile and said parting 80 bead of greater length than the window sashes seated in said channels.

8. A window frame comprising a stile, a parting bead, a tongue extending from said stile beneath said parting bead, said stile 100 bent to form a channel between said parting bead and said stile, a window sash seated in said channel, means for removably securing said parting bead which extend therethrough and into said tongue, other means for removably securing said stile to said frame.

9. A window frame comprising a stile, a parting bead, a tongue extending from said stile beneath said parting bead, said stile bent to form a channel between said parting bead 110 and said stile, a window sash seated in said channel, a plate secured to said frame and extending between said tongue and said parting bead, removable securing means which passes through said parting bead, said plate 115 and into said tongue whereby said stile may be removed without removing said parting bead, and other means for removably securing said stile to the frame.

10. A window frame comprising an inner and outer stile, a parting bead intermediate said stiles to form channels, a tongue extending from said inner stile beneath said parting bead, a strip secured to the frame adjacent the outer stile extending between said tongue and said parting bead, said bead, tongue and strip having apertures therein, a securing means passes through said bead and strip and into said tongue whereby said outer stile may be removed without removing 120 125 130

said parting bead, and wherein the same means may be utilized for removing said parting bead.

11. A window frame having stiles on opposite sides, one of said stiles having a channel formed therein, a sash between said stiles and adapted to slide therein, one side of the sash resting in said channel, means on the unchanneled side for slidably securing said sash in place, removable means in said channel for slidably securing said sash therein and for spacing said sash from the bottom of the channel.

In testimony whereof I affix my signature.

GEORGE W. LANCASTER.
